[57] CLAIM

The ornamental design for a cash dispensing machine,
substantially as shown and described.

DESCRIPTION

FIG. 1 is a front, top and right side perspective view of
a cash dispensing machine showing my new design;

FIG. 2 is a front elevational view thereof;

FIG. 3 is a right side elevational view thereof, the oppo-
site side being a mirror image;

FIG. 4 is a top plan view thereof; and

FIG. 5 is a rear elevational view thereof.

FIG. 1

FIG. 2

FIG. 3

FIG. 4
